Primary Examiner — Karen S Acker(74) *Attorney, Agent, or Firm* — Marshall, Gerstein & Borun LLP(57) **CLAIM**

The ornamental design for a tissue sheet with embossing pattern, as shown and described.

DESCRIPTION

The sole FIGURE is a top plan view of a tissue sheet with embossing pattern showing my new design. The broken line surrounding the drawing depicts the boundaries of the claim and forms no part thereof.

1 Claim, 1 Drawing Sheet(56)
